Primary Examiner — Brett Miller*Assistant Examiner* — Rani J Abdallah(74) *Attorney, Agent, or Firm* — Greenblum & Bernstein, P.L.C.(57) **CLAIM**

I claim the ornamental design for a bottle, as shown and described.

DESCRIPTION

FIG. 1 is a top and front perspective view of a bottle;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is an enlarged cross-sectional view thereof taken along section line 8-8 of FIG. 2; and,

FIG. 9 is a cross-sectional view thereof taken along section line 9-9 of FIG. 4.

This bottle is entirely translucent. The dark, solid lines shown in each of the figures indicate the three-dimensional surface shape of this design, and the light, parallel lines shown in each of the figures indicate the translucency of this design.
